FLORAL VASE OR THE LIKE

Edwin K. Kaelke, Dundee, Ill., assignor to The Haeger Potteries, Inc., Dundee, Ill.

Filed July 15, 1971, Ser. No. 163,140

Term of patent 7 years

Int. Cl. D11—02

U.S. Cl. D29—28

Fig. 1.

Fig. 2.

Fig. 3.

FIG. 1 is a side elevational view of a floral vase showing my new design, the side opposite being identical thereto;

FIG. 2 is a top plan view thereof; and
FIG. 3 is a bottom plan view thereof.

I claim:

The ornamental design for a floral vase or the like, substantially as shown and described.
